SINGLE FLANGE RAIL ANCHOR

Frederick A. Preston, Lake Forest, Ill., assignor,
by mesne assignments, to Poor & Company, Chi-
cago, Ill., a corporation of Delaware

Application February 27, 1947; Serial No. 731,250

5 Claims. (Cl. 238—323)

1

This invention relates to improvements in rail anchoring devices adapted to grip the base portion of a railroad rail and have abutting engagement with a fixed part of the roadbed to resist creeping movements of the rail.

A principal object of the invention is to provide an anchor device of the above general character which is so formed that it will engage only a single flange of a rail base and will maintain its position on the rail by means of a resilient wedge grip on the top and bottom surfaces of said rail base flange.

A rail anchor of the specific type herein contemplated has certain advantages over the anchors which extend entirely across the rail base in that it can be economically made from sheet metal as distinguished from metal bars. Consequently the present anchor can be made by simplified pressing and bending operations and can be readily applied on a rail base flange in a position to extend into the space between the rail and the top face of a crosstie so as to abut against a vertical edge surface of the tie-plate. The anchor, being made of flat metal stock, can be made relatively wide and be formed with a pressed rigidifying corrugations therein at such location that the corrugation will not interfere with the application of the anchor to a rail in a position to overlie the top face of the crosstie.

A further advantage of the present invention, over the above type of anchors which extend entirely across the rail base, is that the present anchor will have holding power substantially equal to the said bar type, but its weight and manufacturing cost are considerably less. Consequently more of the present anchors can be applied to a rail and thereby provide greater holding power per rail without additional cost.

It is therefore an object of the present invention to provide a rail anchor which can be economically made of relatively wide material so as to form surfaces of large area for frictional gripping engagement with the rail base; provide such anchor with adequate reinforcements in the form of a rigidifying corrugation, and which will not score the rail base when it is driven to its applied position on a rail.

The present invention presents another important advantage over known forms of rail anchors which are ordinarily applied by driving them transversely of the rail at locations adjacent the crosstie or the tie-plate, as the case may be. Such anchors are usually applied as closely as possible to the crosstie on the tie-plate, but the applying force is directed at right angles to the

2

length of the rail. Consequently the anchor is not forced into intimate initial contact with the said crosstie or tie-plate. In fact the desired close contact is obtained only by driving the anchor lengthwise of the rail or by an initial creeping movement of the rail in the direction of the crosstie.

One of the important objects of the present invention is to insure intimate initial contact between the rail anchor and the tie-plate, against which it abuts, so as to avoid any lengthwise movement of the rail relative to the tie-plate. In this connection the improved anchor device is provided with an upper jaw which extends diagonally to the length of the rail and is adapted to be driven onto the rail in a diagonal direction toward the tie-plate, whereby the applying force will drive the anchor firmly against an edge surface of the tie-plate. In addition to insuring firm initial contact between the rail anchor on a tie-plate, the tie-plate will be moved lengthwise of the rail to take up any looseness which may exist between the tie-plate and the rail spikes or other devices for fastening said plate to the cross tie.

One approved form of anchor device, constructed in accordance with this invention, is illustrated in the accompanying drawings, wherein:

Fig. 1 is a fragmentary sectional view through the base portion of a railroad rail showing the improved anchor device applied to one flange of the rail base in a position to bear against an edge surface of a crosstie.

Fig. 2 is a plan view of the structure shown in Fig. 1.

Fig. 3 is a side view of the structures shown in Figs. 1 and 2 showing the manner in which the lower jaw member of the anchor device extends into the space between the bottom surface of a rail base and the top surface of a crosstie so as to abut against a tie-plate interposed between the rail and said tie.

Fig. 4 is a plan view of a blank from which the anchor device is formed.

Fig. 5 is a view in plan of the blank after it is bent upon itself to form the improved anchor device.

The invention is illustrated in connection with a fragmentary portion of a railway track including a base portion 10 of a railroad rail, a crosstie 11 and a tie-plate 12. The tie-plate is interposed between the rail base 10 and the top face of the crosstie and is secured in position thereon by means of rail spike 13—13 or other approved forms of fastening devices. The said tie-plate 12

is normally of less width than the crosstie 11. Consequently the edge 14 of the plate is spaced inwardly from the side face of the crosstie as shown best in Figs. 2 and 3 of the drawings.

The improved rail anchor is in the form of a V-shaped device comprising an upper jaw 15, a lower jaw 16, and a bend portion 17 which connects the upper jaw with the lower jaw. The lower jaw extends in a horizontal plane so that the entire area of the flat surface 18 thereof bears flat against the bottom surface 19 and the rail base 10. The upper jaw 15 is inclined relative to the lower jaw 16 at an angle which is slightly less than the slope of the top surface 20 of the rail base so that when the anchor is driven to its applied position the jaw 15 will flex upwardly until the flat bottom surfaces 21—22 thereof bears flat against the inclined surface 20 of the rail base. When this condition occurs, the inner surface 23 of the bend 17 bears against the vertical edge of the rail base. The said bend 17 is preferably so formed as to provide clearance spaces 24 and 25 adjacent the upper and lower corners of the rail base flange so as to avoid binding of the anchor on said corner portions of the rail.

The upper jaw 15 of the anchor, when viewed in plan, is disposed at an angle to the bottom jaw 16 and extends in a direction diagonal to the length of the rail. The end of the bend 17 which is from the tie-plate is flattened to provide a flat striking surface 26 which is normal to the opposite edges of the upper jaw. The said striking surface is formed at the location indicated so that the hammer blows for driving the anchor onto the rail flange will be directed against the said striking surface direction indicated by the arrow in Fig. 2 so as to force the surface 27 of the lower jaw 16 against the edge 14 of the tie-plate when the anchor reaches its final position. This pressure against the edge 14 of the tie-plate will move the plate sufficiently to force the edges 28 of its spike holes into firm contact with the shank portion of the spike 13.

The tie-plate engaging edge 27 of the anchor is preferably cut away at 29 so that the tie-plate engaging surface will be confined to a space less than the full length of jaw 16 and thereby prevent the end portion of the lower jaw from engaging the tie-plate.

The anchor device is rigidified by a centrally located corrugation. The portion 30 of the corrugation which extends around the bend 17 preferably extends parallel to the side edges of the lower jaw. The portion 31 which rigidifies the upper jaw 15 extends parallel to the side edges of the jaw. The ends of the jaws 15 and 16 are preferably rounded to prevent scoring of the rail when the anchor is driven to its applied position.

The blank from which the anchor is formed is shown in Fig. 4. It consists of a main body portion 32 and an angularly disposed end 33. The rigidifying is pressed in the blank. The portion 30, it will be seen, is parallel to the side edges of the body 32 and the portion 31 is parallel to the side edges of the angular end portion 33 of the blank. The blank is bent upon itself about the dot and dash lines 34 and 35 to the position shown in Fig. 5. In this position the angular portion 33 of the blank constitutes the upper jaw 15 of the anchor.

I claim:

1. A rail anchor comprising an upper jaw and a lower jaw which together engage and grip the top and bottom surfaces of one base flange of the rail, the said lower jaw being positioned to ex-

tend transversely beneath the rail base at substantially right angles to the length of the rail and the said upper jaw being disposed at an angle to the lower jaw to extend over the top surface of the said base flange in a direction diagonal to the length of the rail, and means defining a flat striking surface, the plane of which extends at substantially right angles to the longitudinal center of the upper jaw, whereby the application of force is normally delivered to said striking surface in a direction aligned with the upper jaw.

2. A rail anchor comprising an upper jaw and a lower jaw which together engage and grip the top and bottom surfaces of one base flange of the rail, the said lower jaw being positioned to extend transversely beneath the rail base at substantially right angles to the length of the rail and the said upper jaw being disposed at an angle to the lower jaw to extend over the top surface of the said base flange in a direction diagonal to the length of the rail, and means defining a striking surface, the plane of which extends at substantially right angles to the longitudinal center of the upper jaw and is located at one side of said longitudinal center whereby force applied to said striking surface forces the anchor device in a diagonal direction onto the base flange of the rail.

3. A rail anchor comprising an upper jaw and a lower jaw which together engage and grip the top and bottom surfaces of one base flange of the rail, the said lower jaw being positioned to extend transversely beneath the rail base at substantially right angles to the length of the rail and the said upper jaw being disposed at an angle to the lower jaw to extend over the top surface of the said base flange in a direction diagonal to the length of the rail, means defining a flat striking surface, the plane of which extends at substantially right angles to the longitudinal center of the upper jaw, whereby the application of force is normally delivered to said striking surface in a direction aligned with the upper jaw, and a pressed reinforcing corrugation, a portion of which extends longitudinally of the upper jaw and parallel to said longitudinal center and another portion of which extends parallel to the longitudinal center of the lower jaw.

4. In a railway track structure for resisting creeping movement of a railroad rail including a rail, a tie-plate on which the rail is supported, a crosstie, and means extending through openings in the tie-plate to fasten said plate to the crosstie; of a rail clamp adapted to be driven into frictional holding engagement with the top and bottom surfaces of the rail base; said clamp comprising a lower jaw adapted to extend beneath the rail base at substantially right angles to the rail and bear against an edge of the tie-plate, an upper jaw positioned at an angle to extend in a direction diagonal to the length of the rail and in a direction toward said tie-plate, and means defining a flat striking surface at one side of the longitudinal center of the anchor device, the plane of said striking surface being positioned at right angles to the longitudinal center of the upper jaw, whereby the force for driving the anchor onto the rail is normally applied to said striking surface in a direction aligned with said upper jaw, so as to simultaneously force the anchor into firm engagement with the crosstie and also force the plate into firm engagement with its fastening means; the inner end of said

lower jaw being cut away to prevent the end thereof engaging the tie-plate.

5. In a railway track structure for resisting creeping movement of a railroad rail including a rail, a tie-plate on which the rail is supported, a crosstie, and means extending through openings in the tie-plate to fasten said plate to the crosstie; of a rail clamp adapted to be driven into frictional holding engagement with the top and bottom surfaces of the rail base; said clamp comprising a lower jaw adapted to extend beneath the rail base at substantially right angles to the rail and bear against an edge of the tie-plate, an upper jaw positioned at an angle to extend in a direction diagonal to the length of the rail and in a direction toward said tie-plate, and means defining a flat striking surface at one side of the longitudinal center of the anchor device, the plane of said striking surface being positioned at right angles to the longitudinal center of the 10 upper jaw, whereby the force for driving the

anchor onto the rail is normally applied to said striking surface in a direction aligned with said upper jaw, so as to simultaneously force the anchor into firm engagement with its fastening means; the tie-plate engaging face of the lower jaw being cut away so as to reduce the tie-plate abutting surface thereof and confine the said tie abutting surface to a location near the outer portion of the anchor device.
